Primary Examiner—Jeffrey Asch

(74) Attorney, Agent, or Firm—Banner & Witcoff, Ltd.

(57) CLAIM

I claim the ornamental design for the key buttons for a handset, as shown and described.

DESCRIPTION

FIG. 1 is a front view of the key buttons for a handset; and, FIG. 2 is a perspective front side view thereof.

The broken line showing of environment in the figures is for illustrative purposes only and forms no part of the claimed design.

1 Claim, 2 Drawing SheetsFIG. 1
